UNITED STATES PATENT OFFICE.

JAMES E. WORSWICK, OF MONTGOMERY, ALABAMA.

DEVICE FOR REMOVING PISTON-RODS FROM CROSS-HEADS.

SPECIFICATION forming part of Letters Patent No. 282,828, dated August 7, 1883.

Application filed May 17, 1883. (No model.)

To all whom it may concern:

Be it known that I, JAMES EDWARD WORSWICK, of Montgomery, in the county of Montgomery and State of Alabama, have invented 5 a new and useful Improvement in Devices for Removing Piston-Rods from Cross-Heads; and I do hereby declare that the following is a full, clear, and exact description of the same.

This invention is designed for the purpose 10 of removing piston-rods from cross-heads without the injury of any part; and it consists in the construction hereinafter described and claimed.

In the accompanying drawings, Figure 1 is 15 a sectional view of the device, showing its application to use; and Fig. 2 is a cross-section on line x x of Fig. 1.

A represents a base-piece, the bearing-surface of which is curved to fit the wrist-pin of 20 the cross-head, as shown.

a represents a stud or projection extending from the base-piece, which is provided with any proper screw-threads.

B represents a cylinder, and B' a feathered 25 nut arranged therein, and provided with threads adapted to engage with the threads of the projection a .

b represents projections upon the extreme 30 surface of the cylinder, by means of which it is adapted to receive any proper form of wrench for turning the same. b' represents a central projection upon the front end of the cylinder, which is adapted to fit the centering-recess in the end of the piston-rod.

To adapt the device for being operated either 35 by a wrench or by hydraulic pressure, I provide the stud a with a central longitudinal bore, c , communicating at one end with the chamber formed by the bottom or closed end of the cylinder B and at the other with a pipe, 40 which is to be connected to a hydraulic jack. The nut B' , screwing on the stud a , is adapted, by means of the feathers d , to have only a longitudinal movement in the cylinder B . The nut B' is adapted to bear against an annular 45 shoulder, e , in the cylinder when the latter is properly operated with a wrench, while hydraulic pressure will cause the nut B' to slide outwardly from the cylinder B sufficiently to withdraw the piston-rod. 50

Having thus described my invention, what I claim as new is—

1. The combination of the base-piece A , having the threaded projection a , provided with the bore c , and the cylinder B , formed with 55 an internal nut, B' , screwing on said projection and connected to the cylinder by feathers d , and adapted to bear against an annular shoulder, e , in the cylinder, substantially as shown and described. 60

2. The device described, consisting of the curved base-piece A , having the threaded projection a , and a nut having a suitable bearing, as and for the purpose set forth.

JAMES EDWARD WORSWICK.
